CLAIM

The ornamental design for a single forefoot magnetic pulse therapy device applicator, as shown and described.

DESCRIPTION

This application is related to U.S. Utility patent application No. 18/905,994, filed on Oct. 3, 2024, entitled “Magnetic Pulse Therapy Device (MPTD) for the Treatment of Pain”. This application is also related to Design patent application No. 29/953,035, filed on Jul. 18, 2024, entitled “Single Foot Applicator for Magnetic Pulse Therapy Device (MPTD)”; Design patent application No. 29/955,533, filed on Aug. 1, 2024, entitled “Single Foot Applicator for Magnetic Pulse Therapy Device (MPTD)”; and Design patent application No. 29/959,319, filed on Aug. 24, 2024, entitled “Two Foot Applicator for Magnetic Pulse Therapy Device (MPTD)”

FIG. 1 is a perspective view of a single forefoot magnetic pulse therapy device applicator;

FIG. 2 is a perspective view thereof;

FIG. 3 is a distal end view thereof;

FIG. 4 is a proximal end view thereof;

FIG. 5 is a side view thereof;

FIG. 6 is a top view thereof;

FIG. 7 is a cross sectional view thereof taken from FIG. 6 at 7; and,

FIG. 8 is a perspective view and section cut thereof taken from FIG. 1 at 8.

(Continued)

The broken lines depict portions of the single forefoot magnetic pulse therapy device applicator and form no part of the claimed design.
